Z. ECKELBARGER

SOUND REPRODUCING DEVICE

Filed Sept. 9, 1920

Witness:

C. Towsley.

Inventor

Zera Eckelbarger

By Louis C. Vanderlip

Attorney

UNITED STATES PATENT OFFICE.

ZENA ECKELBARGER, OF GOSHEN, INDIANA.

SOUND-REPRODUCING DEVICE.

Application filed September 9, 1920. Serial No. 409,292.

To all whom it may concern:

Be it known that I, ZENA ECKELBARGER, a citizen of the United States, residing at Goshen, county of Elkhart, Indiana, have 5 invented certain new and useful Improvements in Sound-Reproducing Devices, of which the following is a specification.

My invention relates to reproducers for use in sound reproducing machines, and especially to the stylus and stylus bar thereof.

The main object of my invention is the production of a multistylus device which when applied to a sound reproducing machine will enable the machine operator to 15 play or reproduce the sound from any existing musical or sound reproducing record. Other objects of my invention are mentioned and described herein.

The preferred embodiment of my invention is illustrated in the accompanying drawing in which Figure 1 is a side elevation of my invention applied to the sound box and tone arm of a sound reproducing machine; Fig. 2 is an enlarged plan view of 20 the invention showing its connection with and relation to the sound box, and showing also the pivotally mounted stylus arms; Fig. 3 is a fragment showing one of the stylus arms in operative position and the others inoperative; Fig. 4 is a view showing the sound box swung at a different angle or plane to enable the engagement of a different record; Fig. 5 is a section taken on the line 5—5 of Fig. 2; Fig. 6 is a fragment 25 in section of the tone arm and sound box connection; and Fig. 7 is a section taken on the line 7—7 of Fig. 6.

Similar numerals of reference indicate like members and parts of members throughout the several views on the drawing.

On the drawing, the numeral 1 indicates a fragment of a tone arm of a sound reproducing machine and numeral 2 an extension thereof, one end whereof is revolvably fitted within the tone arm socket 3. The numeral 4 indicates a slot formed in the wall of the end of member 2 and extending circumferentially thereof, into which slot a stop pin 5 projects, said pin being 45 mounted in the wall of the socket member 50

3, whereby the arm extension 2 may be rotated in said socket for a half circle and stopped at a predetermined point. The numeral 6 indicates a bend portion of the tone arm extension 2 with which the sound box 7 55 is revolvably connected, as hereinafter described and illustrated in Fig. 6 of the drawing.

Numeral 8 indicates the sound box bearing bore within which is arranged the bearing portion 9 of the tone arm bend 6, the shoulder 10 thereof being engaged by the body of the box 7. Numeral 11 indicates a nut screw threaded upon the lower end of the bearing portion 9 and against which a 60 wave spring washer 12 bears, said washer encompassing the member 9 between the nut 11 and sound box body and is adapted to prevent vibration of the parts as well as casual rotation of the sound box 7. The 65 sound box 7 is adapted to be rotated on its bearing 9 within certain limits less than a half circle, to effect which function the arcuate slot 14 is formed in the body 7, which slot is engaged by a stop lug 13 carried by the tone arm bend 6. See Fig. 7.

The numeral 15 indicates a vibratory stylus bar of any suitable material or form, which bar is connected with the diaphragm (not shown) mounted in the sound box 7. 80 The bearing end of the stylus bar 15 is provided with a hub member 15' from which the opposed trunnion members 16 and 17 project, said trunnion members having cone bearing connections with the conically 85 pointed bearing pins 18 and 19 which are screw threaded into the bearing brackets 20 and 21 to enable adjustment of said pins. The numeral 22 indicates a stylus carrier the forward end 23 whereof may be screw 90 threaded into a socket 24 formed in the hub 15' axially of the stylus bar 15, said carrier being provided with the cylindrical bearing portion 25 adjacent the stud portion 23.

Numeral 26 indicates a multistylus member provided with the bore 26' within which bore the bearing portion 25 of the carrier 22 is arranged, said member 26 being adapted for rotation thereon within certain pre- 100

determined limits. Numerals 27 and 28 indicate stylus arms projecting from the carrier member 26 at substantially opposite positions thereon and spaced from each other by substantially one hundred eighty degrees, said arms being provided with the points 29 and 30, respectively, which points are parts of well known devices now in common use and each adapted to play, or 10 engage operatively, a different kind of sound reproducing record. The numeral 31 indicates a needle socket formed in the member 22 and substantially axially of the socket 23, said socket being adapted to receive 15 and contain a fibre or metal stylus or needle of any suitable shape of a well known make now in extensive use and adapted to engage a sound reproducing record, which needle may be secured within said socket 20 by a set screw 32 carried by the member 22.

Numerals 33 indicates a stop lug projecting from the face of the hub member 15' and extending into the arcuate slot 34 25 formed in the opposing face of the bearing hub or member 26, the end walls of said slot being adapted to serve as abutments to arrest said stop lug and to prevent the multi-stylus member 26 from rotary movement 30 beyond predetermined positions. The numeral 35 indicates a wave spring washer mounted upon the end of the bearing 26' and between the carrier 26 and the shoulder 36 of member 22, which washer is adapted to engage and exert a resilient thrust upon the member 26 to prevent vibration thereof as well as casual rotation thereof.

It should be appreciated that the sound box 7 may be of any suitable construction 40 or design, and that the joint connecting the arms 1 and 2 may be of the structure and design shown and described herein or similar to that shown and described in my United States Patent No. 1,269,266, June 11, 45 1918, to enable the rotation of the arms 2 through an arc of one hundred eighty degrees. When the sound box 7 and arm 2 are positioned as indicated in Fig. 1 of the drawing, either of the stylus arms 27 and 50 28 may be brought into operative position by rotating the member 26 a half revolution, thereby enabling the operator to reproduce sound from two different kinds of sound reproducing records. See also Fig. 3 which is 55 a fragmentary view showing the stylus arm 27 in operative position and with the arm 28 swung opposite thereto. In Fig. 4 a third position of the stylus carrier is shown, whereby a third kind of sound reproducing 60 record may be used, which position is gained by rotating the arm 2 through one hundred eighty degrees and effecting a partial revolution of the sound box 7 on its bearing 9 subsequent thereto, whereby the needle 65 socket 31 is brought into operative position,

as indicated in said figure of the drawing.

It should be appreciated that the function of the spring washer 35 is important for it serves to maintain the juxtaposition of the carrier member 26 at all times, especially 70 when the stop lug 33 is in engagement with either end wall of the arcuate slot 34 when either of the arms 27 and 28 is brought into operative position, as described.

I claim:

1. In combination with a stylus bar, a stylus carrier extending axially with respect thereto; and a plurality of stylus carriers movably associated therewith and extending radially therefrom said carriers being adapted to hold different types of stylus members in position for playing different forms of disk records.

2. In combination with a sound arm, a sound box arranged with its axis transverse to that of said arm, said sound box being rotatable about the axis of the arm and about its own axis; a stylus bar carried by the box; a stylus carrier fixedly mounted on the stylus bar, and another stylus carrier movably mounted on said bar, said carrier being adapted to assume operative positions upon movement of said sound arm to different positions with respect to said sound arm.

3. In combination with a sound box, a stylus bar pivoted thereto; a shaft in alignment with the bar and carried thereby; stylus carriers rotatable about the shaft; and a stylus carrier in alignment with the bar.

4. In a device of the class described and in combination with a sound box, a stylus bar pivoted thereto; a shaft in alignment with the bar and carried thereby; a stylus carrier rotatable about the shaft; and a stylus carrier in alignment with the bar.

5. In a device of the class described and in combination with a sound box, a stylus bar pivoted thereto; a shaft in alignment with the bar and carried thereby; a stylus carrier rotatable about the shaft; and a socketed stylus carrier in alignment with the bar.

6. The combination with an adjustable sound box, of a stylus bar having an axially extending stylus holding member at its free end for use when the sound box is adjusted in one position, and a multiple stylus carrier rotatably mounted around an intermediate portion of said arm for use interchangeably when the sound box is adjusted in another position.

7. In a device of the class described and in combination with a sound box, a stylus bar pivoted thereto; a shaft in alignment with the bar and detachably carried thereby; a stylus carrier rotatable about the shaft; and a stylus carrier in alignment with the bar and carried by said shaft.

8. The combination with an adjustable

sound box, of a stylus bar having axially extending stylus holding means at its free end for use when the sound box is adjusted in one position, a multiple stylus carrier rotatably mounted around an intermediate portion of said bar, and different types of stylus members mounted upon said carrier for use interchangeably with one another when the sound box is adjusted in another position. 10

In testimony whereof I have hereunto affixed my signature this 7th day of September, 1920.

ZENA ECKELBARGER.
